UNITED STATES PATENT OFFICE.

EDWARD RUFF AND ELMER C. L. BAILEY, OF NEWARK, NEW JERSEY.

AUTOMATIC RECIPROCATING BOLT.

Application filed July 8, 1926. Serial No. 121,228.

This invention relates to bolts such as are used for fastening doors and the like and has special reference to an automatic reciprocating bolt provided with a locking 5 cam or latch.

One important object of the present invention is to improve the general construction of a device of this character.

A second important object of the invention 10 is to provide a novel arrangement of reciprocating bolt and latch member wherein the latch member is automatically operated to hold the bolt securely in its closed and opened positions.

A third important object of the invention 15 is to provide novel latch means in such a bolt automatically controlled by the mechanism that moves the bolt itself.

A fourth important object of the invention 20 is to provide a bolt of this character having electro-magnet means for operating the bolt so arranged as to be capable of being controlled from a distance.

With the above and other objects in view 25 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of the improved 35 bolt.

Figure 2 is a side elevation thereof, partly broken away, and showing the bolt as applied to a door.

Figure 3 is an end view of the device.

Figures 4, 5 and 6 illustrate successive 40 positions of the latch mechanism during the movement of the bolt from open to closed position.

Figure 7 is a view similar to Figure 2 showing the bolt fully closed.

Figure 8 is a wiring diagram of the invention.

In the embodiment of the invention here shown there is provided a bolt 10 suitably mounted in a casing 11. At one end of this casing is a housing 12 having side walls 13 between which extends the corresponding end of the bolt 10. At this end the bolt is provided with a pair of spaced upstanding arms 14 and secured in the walls 13 is a pivot pin 15 which lies between the arms

14. On this pivot pin is mounted a latch member which consists of a pair of plates 16 arranged in V-shaped relation, the apex of the V being carried by the pivot pin. 60 These plates are of such length that upon the bolt being moved to its fully opened or fully closed position, one of the plates will lie parallel to and rest on the bolt with its end engaging a respective arm 14 so that 65 the bolt cannot be moved until the latch is lifted.

In order to lift the latch and move the bolt there is provided a plunger 17 of iron or the like and this plunger is mounted to 70 slide through a pair of solenoids 18 and 19 so that when one of these solenoids is energized the plunger is drawn in one direction while energization of the other solenoid moves the plunger in the opposite direction. 75 This plunger has one end extending over the arm provided end of the bolt and this end carries a pin 20 which has its extremity positioned between the plates 16 at their diverging ends.

The solenoids may have their adjacent 80 ends connected to a battery 21 by wires 22 and the remaining ends connected to wires 23 to the fixed contacts of a single pole double throw switch 24 which has its fixed 85 contact connected to the battery 21.

To understand the operation we will suppose the parts to be in the position shown in Figure 2. To lock the bolt the switch is moved to energize the solenoid 19. Thereupon the pin 20 contacts with the upper plate 16 and swings it to the position shown in Figure 4. Following this the pin still moves in the same direction and passes through the positions shown in Figures 5 90 and 6 until it reaches the position shown in Figure 7 at which time the left hand arm 14 engages the apex of the plates and stops further movement. The bolt cannot now be moved backwardly because the plate 16 which is now in horizontal position locks the same. Obviously to open the bolt the solenoid 18 is energized and the reversed movement takes place.

There has thus been provided a simple 100 and efficient device of the kind described and for the purpose specified.

It is obvious that minor changes may be made in the form and construction of the invention without departing from the material spirit thereof. It is not, therefore, desired to confine the invention to the exact 110

form herein shown and described, but it is desired to include all such as properly come within the scope claimed.

Having thus described the invention, what is claimed as new, is:

- 5 1. In a locking device, a sliding bolt having a pair of spaced arms at one end, a latch member positioned between said arms and pivoted at one of its edges to points adjacent the bolt, said latch member being tilt-
10 able to swing between positions on opposite sides of its pivotal axis and engage respective arms, an electro-magnetically controlled plunger extending parallel to the bolt, and
15 a finger on said plunger projecting into the space between the arms and engaging the latch member to tilt the same.
2. In a locking device, a sliding bolt having a pair of spaced arms at one end, a latch member positioned between said arms and pivoted at one of its edges to points adjacent the bolt, said latch member being tilt-
20 able to swing between positions on opposite sides of its pivotal axis and engage respective arms, an electro-magnetically controlled plunger extending parallel to the bolt, a finger on said plunger projecting into the space between the arms and engaging the latch member to tilt the same, a pair of
25 solenoid coils surrounding the plunger in longitudinally spaced relation, said plunger being of magnetic material to form the core for said solenoids, and means for selectively energizing said solenoids.
- 30 3. In a locking device, a sliding bolt having at one end a pair of spaced arms extending at right angles to the bolt from the same side thereof, a housing at the arm provided end of the bolt having walls on each side thereof, a latch member having a pair of plates in V-shaped relation, said plates being pivoted to said walls at the apex of the
35 V and each being of such length as to engage a respective arm upon movement on the

45 pivot to position parallel to the bolt, and means to engage and tilt the plates and to engage the arms and move the bolt.

4. In a locking device, a sliding bolt having at one end a pair of spaced arms extending at right angles to the bolt from the same side thereof, a housing at the arm provided end of the bolt having walls on each side thereof, a latch member having a pair of plates in V-shaped relation, said plates being pivoted to said walls at the apex of the V and each being of such length as to engage a respective arm upon movement on the pivot to position parallel to the bolt, a plunger mounted for longitudinal movement parallel to the bolt, a finger carried by one end of the plunger and projecting into the space between the divergent ends of the plates, and means to reciprocate the plunger.

5. In a locking device, a sliding bolt having at one end a pair of spaced arms extending at right angles to the bolt from the same side thereof, a housing at the arm provided end of the bolt having walls on each side thereof, a latch member having a pair of plates in V-shaped relation, said plates being pivoted to said walls at the apex of the V and each being of such length as to engage a respective arm upon movement on the pivot to position parallel to the bolt, a plunger mounted for longitudinal movement parallel to the bolt, a finger carried by one end of the plunger and projecting into the space between the divergent ends of the plates, said plunger being of magnetic material, a pair of solenoid coils surrounding said plunger and spaced longitudinally thereof, and means for selectively energizing the coils.

In testimony whereof we affix our signatures.

EDWARD RUFF.
ELMER C. L. BAILEY.
